UNITED STATES PATENT OFFICE.

JOHAN AUGUST DAUGAARD, OF COPENHAGEN, DENMARK.

MECHANISM FOR OPERATING CUTTING APPARATUS OF MOWING-MACHINES.

SPECIFICATION forming part of Letters Patent No. 651,700, dated June 12, 1900.

Application filed November 1, 1899. Serial No. 735,515. (No model.)

To all whom it may concern:

Be it known that I, JOHAN AUGUST DAUGAARD, engineer, a citizen of Denmark, and a resident of 1 Helgolandsgade, Copenhagen, in the Kingdom of Denmark, have invented certain new and useful Improvements in Mechanism for Operating the Cutting Apparatus of Mowing-Machines, of which the following is a specification.

10 The present invention refers to improvements in mechanism for operating the cutting apparatus of mowing-machines. The mechanism is characterized thereby that, contrary to the custom followed up to now, no cog-wheels are used for transmitting the moving power from the axle of the machine to the connecting-rod actuating the knives of the cutting apparatus.

20 The invention is shown on the accompanying drawings, in which—

Figures 1 and 2 represent a mowing-machine having the said moving mechanism, seen, respectively, from above and in side elevation. Figs. 3 and 4 represent details.

25 *a* is the wheel-axle, on which the driving-wheels *b* are placed in the usual manner. On the axle *a* is further arranged a wheel *c*, which by means of a coupling arrangement and during the working of the machine may be made

30 either to follow the movement of the axle or remain loosely on same. As shown in Figs. 2 and 4, the tire or rim of the wheel *c* is formed as an undulating or wavy line. Closely outside the rim of the wheel is arranged a bolt *d*,

35 which is carried partly by an arm *e*, fastened onto the frame of the machine, and partly by a second arm *f*, passed around the axle outside the wheel *c*. On the bolt *d* is arranged an oscillating three-armed crank-lever, two

40 arms *g* of which are provided with rollers *h*, that just touch the wavy rim of the wheel *c*. The distance between these two rollers is so regulated that the one is in contact with the top of a wave or undulation when the other

45 is in contact with a hollow between two waves, and it will therefore be obvious that the three-armed crank-lever obtains a to-and-fro swinging movement around the bolt *d* as the wheel *c* turns.

50 The swinging movement of the crank-lever is transmitted to the cutting apparatus *i* of the machine by means of a crank-lever *l* *u*,

arranged to move round a bolt *k* upon the machine-frame and which with the one arm *u* is connected to the third arm of the above-described three-armed crank-lever and with the other arm *l* to a connecting-rod *n*, the other end of which engages or grips the knife of the cutting apparatus *i*. The end of the arm *u* projects into a hole *t*, Fig. 4, arranged 55 in a lug *v*, forming the prolongation of the arm *m*. As the arm *m* turns round the bolt *d* and the arm *u* round the bolt *k*, the arm *m* must be so arranged that it may alternately be lengthened and shortened, as otherwise a 60 breakage of the machine would occur. For this purpose the lug *v* is provided with a pin *w*, that may slide freely into a corresponding hole in the arm *m*. The lug *v* may thus alternately move away from and draw near to 65 the bolt *d*, around which the arm *m* is swinging, the length of the arm *m* accommodating 70 itself to the movement of the lever *u*.

By regulating the length of the arms of the crank-lever in a suitable manner the necessary movement of the knife may be obtained, even with very flat waves upon the rim of the wheel *c*.

The cutting apparatus is arranged in the usual manner and may be raised from the 75 ground when not used. The cutting apparatus is for this purpose attached to a frame *q*, that may move round the bolts *o* and *p*, and which may be raised and lowered by means of a lever *s*.

80 As the angular movement of the three-armed lever is reduced when the summit of the waves of the wheel *c* is worn, the downward arm *l* of the crank-lever must be so arranged that it may easily be lengthened a 85 distance corresponding to the wear of the wheel *c*, whereby the movement of the knife *i* always remains the same.

Having now particularly described and ascertained the nature of this said invention 90 and in what manner the same is to be performed, I declare that what I claim is—

1. In a harvester, a rotating wheel *c* with a wavy or undulating rim, in combination with a movable three-armed crank-lever arranged 100 adjacent to the rim of the said wheel, and whose two arms *g* are provided with rollers *h* that roll upon the rim of the wheel *c*, the distance between these rollers being such that

the one roller touches the summit of a wave simultaneously with the other one touching the bottom of the curve between two waves, a crank-lever *l u* having one arm connected 5 with the third arm of the three-armed crank-lever, said crank-lever being mounted on a horizontal pivot in advance of the wheel and a connecting-rod *n* connected with the other arm of said crank-lever, the other end of said 10 connecting-rod being movably attached to the knife.

2. In a harvester, the combination with a driven wheel having an undulating periphery, of a three-armed lever having two of its 15 arms engaging the undulating periphery of said wheel, the third arm of said lever being provided with a sliding extension, a crank-lever having one of its members connected with the sliding extension of the three-armed 20 lever, and a pitman for operating the cutter-

bar, connected with the other member of the crank-lever, substantially as described.

3. In a harvester, the combination with a driven wheel having an undulating periphery, of a three-armed lever having two of its 25 arms engaging the undulating periphery of said wheel, the third arm of said lever being provided with a socket in its end, a lug having a pin fitting in the socket of the arm of said lever, a crank-lever having one member 30 connected with said lug, and a pitman for operating the cutter-bar, connected with the other member of the crank-lever, substantially as described.

Signed at Copenhagen, in the Kingdom of 35 Denmark, the 11th day of October, 1899.

JOHAN AUGUST DAUGAARD.
